(57) **CLAIM**

The ornamental design for a combined document list and record for a display screen, as shown and described.

DESCRIPTION

FIG. 1 is a front view of a combined document list and record for a display screen;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof.

The broken line disclosure of display text and graphic images in all views is for illustrative purposes only and forms no part of the claimed design.
